UNITED STATES PATENT OFFICE.

WILLIAM H. POLLGREEN, OF BISBEE, ARIZONA.

DESIGN FOR A POISON-BOTTLE.

46,620.

Specification for Design.

Patented Nov. 3, 1914.

Application filed August 26, 1914. Serial No. 858,751. Term of patent 14 years.

To all whom it may concern:

Be it known that I, WILLIAM H. POLLGREEN, a citizen of the United States, residing at Bisbee, in the county of Cochise and State of Arizona, have invented a new, original, and ornamental Design for Poison-Bottles, of which the following is a specification, reference being had to the accompanying drawing, forming part thereof.

The figure is a view in front elevation of a poison bottle, showing my new design.

I claim:

The ornamental design for a poison bottle, as shown.

WILLIAM H. POLLGREEN.
